US00D912640S

(12) **United States Design Patent** (10) Patent No.: **US D912,640 S**
(45) Date of Patent: ** Mar. 9, 2021

(54) **MOBILE PHONE**

(71) Applicant: **HUAWEI TECHNOLOGIES CO., LTD.**, Shenzhen (CN)

(72) Inventors: **Qian Wang**, Xi'an (CN); **Xiaoyuan Wang**, Xi'an (CN)

(73) Assignee: **HUAWEI TECHNOLOGIES CO., LTD.**, Shenzhen (CN)

(**) Term: **15 Years**

(21) Appl. No.: **29/694,891**

(22) Filed: **Jun. 14, 2019**

(30) **Foreign Application Priority Data**

Dec. 14, 2018 (CN) 201830728040.7

(51) LOC (13) Cl. **14-03**

(52) U.S. Cl.

USPC ..... **D14/138 G**
